UNITED STATES PATENT OFFICE.

CHARLES W. LANPHER, OF NORWICH, NEW YORK.

VACUUM-BRAKE.

SPECIFICATION forming part of Letters Patent No. 243,074, dated June 21, 1881.

Application filed April 24, 1880. (No model.)

To all whom it may concern:

Be it known that I, CHARLES W. LANPHER, a citizen of the United States, residing at Norwich, in the county of Chenango and State of New York, have invented certain new and useful Improvements in Automatic Vacuum-Brakes; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to improvements in automatic vacuum-brakes for railroad-cars and other vehicles in which the normal pressure of the atmosphere is used as the motive force for applying and releasing the brakes; and the objects of my improvements are, first, to provide a cylindrical or otherwise formed vessel in which a constant vacuum is maintained when the motor is in operation, and in which there are placed pistons or other moving parts capable of being operated by the atmosphere as it rushes in when permitted to fill the vacuum; second, to provide a brake-operating mechanism in the cylinder or other vessel of which a vacuum may be maintained at pleasure upon either or both sides of the pistons or moving parts, and into either side of which air can be admitted at pleasure for applying or releasing the brakes; third, to provide a brake mechanism in which atmospheric pressure and a vacuum are made available for releasing the brakes and for returning the parts of the mechanism to their normal positions; fourth, to provide a brake mechanism which, when trains of cars are accidentally separated when in motion, shall automatically apply the brakes to the rear or detached portion, which is regarded as an important feature of my invention. I attain these objects by the mechanism illustrated in the accompanying drawings, in which—

Figure 1 is a side elevation of a locomotive, tender, and one car, showing in part my improved mechanism applied thereto. Fig. 2 is a plan view, showing a portion of a car, the brake cylinder in section, an auxiliary vacuum-vessel, pipes which conduct the air to the

brake-cylinder and from it to the exhausting apparatus, an air-pump for maintaining a constant vacuum between the pistons and in the ends of the cylinders, an ejector or any other air-exhausting device operated by steam, which may be used, in conjunction with the pump or independent of it, for removing the air from between the pistons and the ends of the cylinder, with cocks or valves for controlling the egress and ingress of air from and to said cylinder, and flexible hose for uniting the pipes between the different cars or between the cars and the engine. It also shows the method of attaching the pistons or other moving parts within the cylinder or other vessel to the brakes. Fig. 3 shows auxiliary vacuum-vessels with pipes for connecting them to each other and to the brake-cylinder, with a valve for controlling the passage of the air from one to the other or for preventing such passage; and Fig. 4 is a sectional view of a three-way cock for controlling the passage of air through the conducting-pipes which extend from the engine to the different cars of the train.

Similar letters refer to similar parts throughout the several views.

In constructing and applying my improved brake mechanism there is employed an air-pump, A, or an air-ejector, of any approved form of construction, which may be placed under the foot-board of the engine, or in any other convenient location where it can be driven by an auxiliary engine, with steam taken from the generator; or it may be driven from some moving part of the locomotive or actuated in any other known and convenient manner. This pump or ejector is to be supplied with the requisite valves for controlling the ingress of air thereto and its egress therefrom, and it is connected by a pipe, A', with a pipe, A'', which has two branches, A''' and A'', connecting it to pipes A⁵ and A⁶, the latter being attached to each of the cars of the train and connected between each by means of flexible pipes or hose in the usual or any convenient manner. Under each of the cars, and under the tenders, if desired, there is placed a cylindrical or otherwise formed vessel, B, which contains two pistons, which, when the brakes are not applied to the wheels, are in the positions shown in Fig. 2 of the drawings. These pistons or

moving parts are to be suitably packed, so that no air can pass them while being moved into their proper positions for applying the brakes, or while holding them in their applied 5 positions. The cylinder or vessel is provided with heads, which are packed to prevent leakage, and have at their centers apertures, through which pass rods B' B², to the outer ends of which chains or ropes are connected, 10 which lead to rods the opposite ends of which are attached to the levers which operate the brakes. The cylinder above alluded to may be of ordinary construction, or of any form that will permit the passage of the pistons or moving parts B³ B⁴; but it is to have upon one of its sides a passage, B⁵, for conducting air to and from the ends thereof, or two branch pipes may be connected, one at each end of cylinder, leading to main pipe A⁵. To the central 15 portion of said cylinder there is attached a pipe, B⁶, through which communication is formed with the pipe A⁶, and with the air or exhaust pump A, or its equivalent exhausting device, the arrangement of these parts being 20 such that when the pump or its equivalent is in operation, and the cars are connected to the engine, a constant vacuum is maintained in said pipes A⁵ and A⁶, and in that portion of the cylinder which is between the pistons, and 25 also on the outer sides of the pistons, or in 30 ends of cylinder.

As an auxiliary to the pump A, but capable of being used as an independent device in case of any derangement of said pump or its equivalent, there is placed upon some convenient part of the generator or upon some portion of the tender or train an ejector, C, or equivalent device, which in the example here shown is illustrated as being attached to the generator 35 between the driving-wheels and near the engineer's position when on duty, and which 40 is connected with the generator by a pipe which conducts the steam to it. It is also connected with the pipes A⁵ and A⁶ in such a manner 45 that the air may be by it exhausted from them and from the cylinder B. It is obvious, therefore, 50 that should the pump A or its equivalent become disabled, or its parts deranged, the ejector or its equivalent may be brought into 55 use and a vacuum maintained in the pipes and cylinder; and it is also obvious that either of the exhaust devices may be used separately 60 for maintaining the vacuum, and that should either of them become partially or wholly inoperative the other may be relied upon as a 65 means of maintaining such vacuum in the pipes and cylinder. Any suitable form of ejector or equivalent exhaust device may be used for this purpose, it being only requisite that its 70 construction be such that it shall act upon the air in such a manner as to exhaust it, as above described, and that it shall be furnished with a cock or valve, C², for preventing the ingress of air to the pipes when the exhaustion is being performed by its alternative or principal 75 exhausting device.

In order that the above-referred-to functions may be performed by the devices named, there is placed in each of the branch pipes A² and A³ a three-way cock or a valve which is 80 capable of closing the communication between the exhaust devices and the pipes A⁵ and A⁶, or either of them, at the pleasure of the operator. One form of such device is shown in Fig. 4 of the drawings, which consists of a 85 three-way cock, and is designated in said figure and in Fig. 2 by the letters and figures C³ and C⁴. The relation of the cocks or valves C³ and C⁴ to the pump A, ejector C, pipes A⁵ and A⁶, and the cylinder B is such that when 90 it is desirable to exhaust the air from the cylinder for the purpose of applying the brakes, the keys of said cocks are placed in the position shown in Fig. 4, so that a free communication exists between the pump or other exhausting device and cylinder, and consequently 95 the air will be exhausted therefrom and from the line of pipes A⁵ and A⁶, at which time the cocks of valves C³ and C⁴ will be so arranged as to exclude the air from said pipes, and the 100 pistons will be at or near the ends of the cylinder B, and when it becomes necessary to apply the brakes all that is required is to change the position of the key in cock C³, so as to establish a communication between the atmosphere and the pipe A⁵, and also by the same motion closing communication with the exhaust devices, when the air will rush in and fill said pipe and pass through the passage B⁵ to the ends of the cylinder and thus force the 105 pistons toward each other, which will have the effect to apply the brakes and keep them set as long as desired; and as during all of this time the air-exhausting device is in operation a vacuum will be maintained between the pistons even though some air should leak past them.

It will be observed that for maintaining the vacuum under the circumstances just named, either the pump or the ejector, or both, or any 110 known exhausting device or devices may be used.

When it becomes desirable to release the brakes it is only necessary to turn back the three-way cock C³ to its original position, so 115 as to open communication through pipes A⁵ to the pump or its equivalent and also to pipe A⁶, thus forming an equilibrium of pressure on both sides of the pistons, when the springs usually applied to the brakes will at once bring 120 the pistons back to the ends of the cylinders. Should it become necessary, however, to instantaneously release the brakes for the purpose of avoiding an accident, the three-way cock C⁴ may be turned, (after the cock C³ is 125 turned to its original position, as above described,) closing the communication to the exhaust device or devices and admitting a rush of air through pipe A⁶ to the center of the cylinder. Now, as the air-pump or other exhausting device has exhausted all air from pipes A⁵ 130 and from the outside of the pistons, it is evi-

dent that the pistons will be instantaneously forced outward to the ends of the cylinder, thus releasing the brakes, as described.

The couplings for connecting the pipes of the different cars of the train and the train to the engine, as before stated, are to be flexible, so as to permit the cars to swing from side to side of the track without straining the pipes, and one of them is to be provided with valves which open outward, so as to prevent the admission of air in case of the accidental parting of the train, they being arranged in the usual manner, so as to be kept open by each other when the train is properly coupled together. This form of coupling and valves being well known need not be further described here. It is necessary to state, however, that in brake mechanism of the type herein described the valves above alluded to are to be used in only one of the pipes, the couplings in the other being without any in order that the air may pass freely through it for applying the brakes and for releasing them in case of emergency, as above stated.

In making provision for automatically applying the brakes in the event of a parting of the train when in motion, there is provided upon each car an auxiliary vacuum-chamber, D, in which there is formed and maintained a vacuum, by the pump A or ejector C, or their equivalents, acting through the pipe A⁵. At the point D' in the pipe which connects the chamber D with the pipe A⁵ there is placed an automatically-operating valve, which, when air is being admitted through the cock C³ for applying the brakes, is closed by the pressure in said pipe, and it is also closed by the same process when any of the couplings in the line of pipes A⁵ are separated. The chamber D is also connected with the cylinder B, at or near its center, as shown in Fig. 2, so that as said cylinder is exhausted chamber D will also be exhausted of air, and thus made to act as an auxiliary to the cylinder, and hence, if any air should leak into said cylinder that was not at once removed by the exhausting mechanism, it would become highly rarefied by having a large space in which to expand, and would offer but little resistance to the movements of the pistons in cylinder B.

It will be seen that in the event of the train becoming separated at any one point the valve in the coupling of pipe A⁵ of the forward part of the detached portion would be closed by the pressure of the atmosphere upon its outer surface, and hence such car and all behind it would have a vacuum formed in their pipes of that line and in their cylinders, as well as in their auxiliary chambers, and that, owing to the fact that the line of pipes A⁵ have no valves in them, air would rush into said cylinders and apply the brakes to the cars of the detached portion of the train. Air would also rush into pipes A⁵ on the part of the train attached to the locomotive, and at once apply the brakes, thereby notifying the engineer of

a detachment, when he could, by turning the cock C⁴, instantly release the brakes and permit that portion of the train to move on, if desired. In this case the engineer has full control of the brakes on the forward detached portion of the train.

I have contemplated the use of one or more auxiliary vacuum-chambers and the requisite pipes and valves for connecting them to each other, as shown in Fig. 3; but it is probable that by the use of a brake-cylinder of the proper dimensions such auxiliary vacuum chamber or chambers may be dispensed with. I however reserve the right to use one or more such chambers if it be found necessary.

I am aware that it is not novel to employ two lines of pipes in constructing a brake mechanism, or to use two pistons in a cylinder in which a vacuum is formed between said pistons by means of an ejector operated by steam, and hence I do not claim, broadly, such devices or the combination thereof irrespective of the functions performed; but

Having thus fully described my invention, what I do claim, and desire to secure by Letters Patent, is—

1. In brake-operating mechanism, the combination of a cylinder or other vessel in which a constant vacuum is maintained when in operation between two pistons or other moving parts and also between the outer surfaces of said pistons or parts and the ends of the cylinders, except when air is admitted to their outer surfaces to apply the brakes, or when air is admitted between them for releasing the same, pipes for conducting air from and to said cylinder or other vessel, and a pump or other exhausting device or devices arranged substantially as described, whereby said exhausting devices are rendered capable of being used jointly or separately, substantially as set forth.

2. In braking mechanism for railroad-cars and other vehicles, the combination of a cylinder, having in it two pistons or moving parts for applying the brakes, two separate and independently-operating lines of pipes for conducting air to and from said cylinder, and one or more air-exhausting devices, the parts being arranged substantially as described, whereby a vacuum may be maintained in the cylinder upon both sides of the pistons or moving parts at pleasure, or upon one side of each only, as set forth, and for the purpose specified.

3. In a braking mechanism, the combination of a cylinder or other vessel having in it two pistons or other moving parts for applying and releasing the brakes, two separate and independently-operating lines of pipes, one of which is provided with automatically-operating valves for use when the train is accidentally separated while running, the other line being without valves, and an air-exhausting device for maintaining a constant vacuum when the train is coupled together and in mo-

- tion, but whereby, when it is desirable to instantaneously release the brakes, air may be admitted between said pistons or other moving parts, substantially as set forth.
- 5 4. In a brake mechanism, the combination of a cylinder or other vessel having three vacuum-chambers, in all of which a constant vacuum is maintained when the train is in motion and the brakes are not required to be applied to the wheels, one or more auxiliary vacuum-reservoirs, pipes leading from said reservoirs to the cylinder or other vessel, and a line of pipes without valves leading from the cylinders placed upon the cars to the exhausting device or devices, whereby, when the train is accidentally separated when in motion, air is automatically admitted to the brake-cylinders or other vessels of the detached portions of the train, and is made to arrest the motion thereof, substantially as set forth.
- 10 5. In a brake mechanism, the combination of two lines of pipes, A⁵ and A⁶, the latter being provided with automatically-operating valves in its couplings, the former being without valves, both lines of pipes being connected with the air-ejecting mechanism, but capable of separate and independent operation, and the three-way cocks C³ and C⁴, the parts being arranged for operation substantially as set forth.
- 15 6. In a brake mechanism, the combination of two lines of pipes extending, when united, the entire length of the train, flexible coupling-hose, cocks or valves for regulating the flow of air from and to the brake-cylinder, and an air-pump or equivalent air-exhausting device, the parts being arranged as described, whereby they are made capable of joint or separate operation at pleasure, as set forth.
- 20 7. In braking mechanism, the combination of an air-exhausting device or of air-exhausting devices, a line of pipes for conducting the air to and from the mechanism, and a cylinder or other vessel containing pistons or other moving parts, the arrangement being substantially such as is herein described, whereby air is removed from and admitted to the vacuum-chambers in the cylinder or other vessel, and is made to act upon one or both sides of the pistons, substantially as and for the purposes set forth.
- 25 In testimony whereof I affix my signature in presence of two witnesses.
